UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

TUCKING ATTACHMENT FOR SEWING-MACHINES.

1,293,725.

Specification of Letters Patent. Patented Feb. 11, 1919.

Application filed July 16, 1917. Serial No. 180,752.

To all whom it may concern:

Be it known that I, ALBERT H. DE VOE, a citizen of the United States, residing at Westfield, in the county of Union and State 5 of New Jersey, have invented certain new and useful Improvements in Tucking Attachments for Sewing-Machines, of which the following is a specification, reference being had therein to the accompanying drawings.

The invention relates to devices for forming and stitching a plurality of tucks in material.

Great difficulty is experienced in inserting 15 or removing work from a multiple tucking guide when there is a large number of folds and consequently it is highly desirable to free the operator's hands as much as possible. To accomplish this the invention contemplates the provision of means for readily 20 operating the components of the tucking guide. When there are a large number of tucks and a correspondingly large number of needles, removal of the work is practically 25 impossible unless the tension on the needle-threads is released when the presser-foot is raised. To enable the work to be removed freely without hindrance is another object of my invention.

Frequently it is desirable to interrupt a 30 tucking operation without disturbing the already formed and stitched tucks in a piece of material. To this end a disconnectible member preferably in the form of a latch 35 is provided for uncoupling the presser-foot and tension release device from a shiftable component of the tucking guide so as to allow the latter to be lifted alone and independently of the former.

Initial crimping of a large number of 40 tucks is difficult and another object of my invention is to provide a construction facilitating the initial formation of the material into tucks.

Briefly the construction comprises a tucking 45 guide having separable components, one of which is disconnectibly latched to a presser-bar which in turn is arranged to actuate a tension release device. A treadle 50 operable lever is positively connected to the presser-bar and a hand lifting lever is arranged to elevate one component of the

tucking guide and separate it from the lower component. A latch movable with and independently of the shiftable component of the 55 tucking guide may be uncoupled from or coupled with the presser-bar so as to permit the upper component of the tucking guide being lifted alone or simultaneously with the presser-bar and tension release device.

In the accompanying drawings, Figure 1 is a plan view of the end of a machine equipped with the attachment. Figs. 2 and 3 are side and rear elevations respectively of the same. Fig. 4 is a detail side elevation of a hand-lifting lever looking off the free end of the overhanging arm and Fig. 5 is a cross section of the tucking guide showing the intermeshing of the upper and lower components thereof.

In its preferred embodiment the invention is applied to a Singer single-chain stitch machine having a plurality of needles 1 arranged in a row at substantially right angles to the line of feed and secured in a needle-clamp 2 at the lower end of a needle-bar 3 operatively mounted in the head 4 at the free end of a bracket-arm 5 overhanging the cloth-surface 6 beneath which are located non-thread carrying loopers (not shown) or such other form of loop-taking mechanism as may be desirable.

A presser-bar 7 pivotally carrying a presser-foot 8 is located in rear of the needle-bar. Secured upon the presser-bar by means of a clamp-screw 9 Fig. 2 is a block or collar 10 embraced within the lateral recess of a sleeve 11 fitted loosely upon the presser-bar. Laterally extending stud-pins 14 and 15 are provided at the upper and lower ends of the sleeve 11, the latter preferably being equipped with an anti-friction roller 16. The stud-pin 14 enters the apertured forward end of a treadle operable lifting lever 17 pivoted at 18 to the rear side of the bracket-arm. Through the lever 17 the presser-bar may be lifted against the action of a flat spring 7' arranged to bear upon the upper end of the presser-bar in a manner well known.

Suitably mounted upon a cloth-plate in advance of the needles in any convenient manner is the lower forming member 19 of a tucking guide having convergent ribs

- 20 terminating in laterally inclined blades which coöperate with tuck guiding blades 21 in a manner fully disclosed in my co-pending application Serial No. 88205, filed 5 April 1, 1916. Above the lower forming member 19 and in intermeshing relationship therewith is an upper forming member 22 of substantially duplicate construction and having secured upon its back or upper face 10 by means of screws 23 a plate 24 carrying a thumb-screw 25 entering a slot 26 in the lateral flange 27 of a laterally bent and upwardly arched arm 28 extending from a position in front of the needles rearwardly 15 under the overhanging arm. At the rear of the needle-bar the arm 28 is bent inwardly as shown at 29 so that when viewed in plan as in Fig. 1, it embraces the head of the machine.
- 20 The arm 28 is slidably supported in rear of the needle-bar in a manner now to be described. A bracket 30 is secured at its upper end by a screw 31, Fig. 1, and at its lower end by a screw 31', Fig. 3, in rear 25 of the head of the machine. This bracket is provided with vertically aligned apertures 32 receiving a pin 33 fixed in the arm 28. The bracket is also provided with a vertically extending stud-pin 34 offset laterally 30 from the line of the apertures 32 and embraced by the slot 35 in the portion 29 of the arm 28. The arm 28 may be lifted or displaced bodily vertically but it is steadied against turning on the pin 33 by means of 35 the pin 34 and slot 35. The upper tuck forming member may thus be lifted in a perpendicular direction away from the lower forming member so as not to disturb the condition of the material in the device 40 when inspection is made thereof.

For convenient elevation of the arm 28 carrying the upper forming member 22 a hand lifting lever 36 is fulcrumed on a stud-pin 37 supported in the head of the machine. A pin 38 preferably carrying an anti-friction roller 39 is eccentrically mounted on the lever 36 which is also cam-faced as at 40 and peripherally recessed as at 41. Coöperating with the roller 38 is the re-entrant curved surface 42 of a vertically arranged plate 43, and coöperating with the cam-face 40 and recess 41 is an anti-friction roller 44 mounted on the plate 43, which it will be noted is adjustably secured by the 50 slot and screw connection shown at 45 to the portion 29 of the arm 28 adjacent the steady slot 35 therein. When the hand lifting lever is thrown upwardly from the position shown in Fig. 2, the upper forming member is elevated.

To lift the presser-foot simultaneously with the upper forming member of the tucking guide a latch 46 is pivoted at 47 to the vertical plate 43 with its toe-portion 47' at 60 a suitable distance away from the pivot in

order to allow the latch to extend beneath the anti-friction roller 16 on the sliding sleeve 11. This latch 46 may be readily swung about its pivot 47 from an operative position under the roller 16 to an inoperative position against the friction of the spring-washer 48 designed to hold the latch in the position desired. With the latch in the position shown in Figs. 2 and 4 (in solid lines) the presser-bar is compelled to 70 move simultaneously with the upper tuck-forming member but with the latch in the dotted line position shown in Fig. 4 the tuck-forming member may be raised without disturbing the material under the presser-foot. The head of a screw 49 tapped into the bracket 30 and locked by a jam nut limits the downward movement of the arm 28 and affords means for determining and varying the space between the tuck-forming members 80 20-22 when material is being operated upon.

As shown in the drawings, the machine is provided with a plurality of tension devices 50 of a number corresponding to the needles 90 with which the tension devices are arranged substantially in parallelism. The tension devices are also symmetrically arranged on opposite sides of a vertical plane containing the needle-bar and preferably also the 95 line of feed. The tension devices 50 are mounted upon a supporting bar 51 carried by the bracket 52 fixedly secured in any suitable manner to the rear of the head 4 of the machine. A vertically arranged pin 53 100 depends from the bracket and a sleeve 54 fitted loosely thereon carries a tension release plate 55 which is arranged to impinge against the pins 56 each entering the bore of the stem 57 about which the separable 105 disks 58 and coiled springs 59 are arranged. When the plate 55 is lifted the tension disks 58 are relieved from the presser spring 59 in a manner fully explained in my Patent No. 1,146,405, July 13, 1915. The tension 110 release plate 55 is preferably lifted, when the presser-bar is raised, by means of a bar or arm 60 seated in a groove 61 in the sleeve 54 and secured by a screw 61' with its free end in the path of movement of the block 115 or collar 10. Gravity is relied upon to hold the tension release plate 55 out of contact with the pins 56 and a collar 62 fast on the lower end of the depending pin 53 determines the lowest position of the tension release plate. 120

Between the multiple tension devices and the needles, which are arranged substantially in parallelism, a take-up 63 is located being arranged preferably symmetrically 125 with respect to a vertical plane through the needle-bar and the line of feed.

The take-up comprises a pair of parallel arms 64-65 mounted in fixed spaced relation on the upper end of the needle-bar, the 130

front one (65) of which is adjustable relatively to the other by means of a well known form of connection indicated at 66. Pivoted on the arm 64 is an L-shaped lever 67 having an apertured cross-arm 68 arranged to operate between and being sustained in parallelism with the arms 64—65. A link 69 pivoted to the finger 70 rising from the head of the machine is pinned to the L-shaped lever 67 as shown at 71 in such wise that the apertured cross-arm 68 of the L-shaped lever is moved differentially between the arms 64—65 fixedly carried by the needle-bar during the operation of the machine. The 15 needle-threads pass from the tensions through eyes in the fixed guide-plate 72 over arm 64 thence through the eyes of the differentially movable cross-arm 68 and over arm 65 to the eyes in the needle-clamp and 20 thus to the needles. By means of the take-up construction the thread leading to the needles is controlled as will be readily understood without further explanation.

From the foregoing description it will be 25 clear that by the provision of a latch or dis-connectible connection between the presser-bar and the upper tuck-forming member the operator will be enabled to manipulate the work with greater convenience than heretofore and without disturbing the condition of 30 the work partly completed when examination is desired of the material in the tucking device.

It will also be noted that the arrangement 35 of the tensions and take up is such that the length of thread between the work and the tension is reduced to a minimum thereby enabling the thread to be controlled with greater reliability than heretofore in this 40 class of machines. By the disposition of the needles, take-up and tension device symmetrically on opposite sides of a vertical plane defined by the needle-bar and the line of feed and also by reason of the relatively 45 parallel arrangement of the before mentioned parts, the action of the thread controlling device is substantially the same on each of the threads running to the needles consequently insuring uniformity in the 50 character of the seamed tucks.

The hand lifting lever 36 has a three-fold utility. It serves to elevate the upper tuck-forming member to allow of convenient manipulation of the work and also, if desired, of the presser-foot and tension release plate as has been previously mentioned. It serves to lock the upper forming member down in normal working relation with the lower forming member so as 55 to guard against accidental disturbance of the tucks under formation through the co-operative action of recess 41 and anti-friction roller 44. It serves as a means for springing or reciprocating the upper forming member preliminary to a stitching op-

eration so as to enable the operator to initially form the crimps or tucks in the material with greater ease than heretofore by reason of the action of the cam-face 40 and fixed friction roller 44, which being positioned a little forward of the main support of the arm 28 exert power in the manner of a lever of the third class to slightly shift or spring the upper tuck-forming member (positioned a relatively long distance from the main support) to and from the lower tuck forming member.

Having thus set forth the nature of the invention, what I claim herein is:—

1. In a sewing machine, in combination, 80 a stitch-forming mechanism including a needle-bar carrying a plurality of needles, upper and lower complemental tuck-forming members located in advance of the needles, an arm carrying said upper member, 85 a support for said arm in rear of said needle-bar, a sliding connection between said support and said arm, and means for bodily lifting said arm and the upper member carried thereby to facilitate manipulation of 90 the work.

2. In a sewing machine, in combination, 95 a stitch-forming mechanism, a presser-foot, a tucking device having complemental forming members, means for supporting said members so as to permit separation thereof for convenient manipulation of work, a lever for shifting one of said forming members relative to the other, and a latch co-operatively arranged between said lever and 100 presser-foot whereby on shifting one of said forming members relative to the other the presser-foot may be lifted.

3. In a sewing machine, in combination, 105 a stitch-forming mechanism, a presser-bar, a presser-foot carried thereby, a tucking device having upper and lower complemental forming members, means for supporting said members so as to permit separation thereof for convenient manipulation of 110 work, a lever for lifting said upper member relative to said lower member, a latch movable bodily with said upper member and also independently thereof, and means operatively connected to the presser-bar, and 115 co-operating with said latch whereby on lifting said upper member the presser-foot may also be lifted.

4. In a sewing machine, in combination, 120 an overhanging arm and a head carried thereby, stitch-forming mechanism, a presser-foot, a presser-foot lifting lever carried by the overhanging arm at the rear of the machine, a tucking device having upper and lower complemental forming members, a 125 lever for shifting said upper forming member toward and from said lower forming member, and a disengageable connection between said shifting lever and said presser-foot whereby the presser-foot may be lifted 130.

by either the presser-foot lifting lever or the shifting lever with or independently of the elevation of said upper member.

5. In a tucking device, upper and lower complementary forming members, an arm carrying said upper member, a lever for lifting said arm to separate said members for convenience in manipulating the work, a locking device for positively holding said members in coöperative tuck-forming relation, and means associated with the locking device for reciprocating said upper and lower members slightly when in tuck-forming relation to facilitate initial crimping of the work.

6. In a tucking device, upper and lower complementary forming members, an arm carrying said upper member, a lever for lifting said arm to separate said members for convenience in manipulating work, said lever having an eccentrically disposed lifting element, and an eccentrically arranged locking recess merging into a cam face, and means connected to said arm coöperating with said lifting element said recess and said cam face whereby the upper forming member may be shifted to assist the operative in handling the work.

7. In a sewing machine, in combination, 30 stitch-forming mechanism including a needle-bar carrying a plurality of needles, an overhanging arm, a head carried by said overhanging arm, a multiple tucking device having upper and lower forming members located in advance of the needles, an arm carrying said upper member and extending from in front of the needles rearwardly of the overhanging arm to the back of the head where it is supported, and means for shifting 40 said arm bodily so as to maintain the upper and lower members relatively parallel in their various spaced positions.

8. In a sewing machine, in combination, 45 stitch-forming mechanism including a needle-bar carrying a plurality of needles, an overhanging arm, a head carried by the overhanging arm, a multiple tucking device having upper and lower forming members located in advance of the needles, an arm carrying said upper forming member and extending upwardly laterally and rearwardly from a point in front of the needles to a point in rear thereof so as not to interfere with the operation of the needles, a bracket for supporting said arm in rear of the needle-bar, a sliding connection between the bracket and the arm, means for shifting said arm relative to said bracket whereby the upper and lower members may be shifted 55 relatively to facilitate the manipulation of the work.

9. In a sewing machine, in combination, 60 stitch-forming mechanism including a needle-bar carrying a plurality of needles arranged in substantially symmetrical relation

to the needle-bar; a multiple tucking device having upper and lower forming members located in advance of the needles, a take-up operated by the needle-bar, and a plurality of thread-guiding arms coöperating with 70 said take-up, a multiple tension device on the thread supply side of said take-up, said multiple tension device being arranged symmetrically with relation to said take-up.

10. In a sewing machine, in combination, 75 stitch-forming mechanism including a needle-bar carrying a plurality of needles arranged in a row at substantially right angles to the lines of seam formation and symmetrical relative to the needle-bar, a 80 multiple tucking device having upper and lower forming members located in advance of the needles, a take-up operated by the needle-bar including thread-engaging members arranged in parallelism with the row of 85 needles, a multiple tension device arranged substantially in parallelism with the row of needles and being arranged symmetrically with respect to a vertical plane through the 90 needle-bar.

11. In a sewing machine, in combination, 95 stitch-forming mechanism including a plurality of needles, a presser-bar, a presser-foot carried thereby, a multiple tucking device including upper and lower forming members, a take-up, a multiple tension device, a lever for separating said tuck-forming members, a latch for disengageably connecting said presser-bar and said upper forming members, and a tension release 100 plate arranged to be operated by said presser-bar whereby said presser-foot may be lifted and said multiple tension device released when said upper forming member is elevated to facilitate manipulation of the 105 work.

12. In a sewing machine, in combination, 110 stitch-forming mechanism including a plurality of needles, a presser-bar, a presser-foot carried thereby, a multiple tucking device having upper and lower forming members, a take-up, a multiple tension device, a tension release plate operated by said presser-bar for relinquishing tension on thread passing to said needles, a presser-foot 115 lifting lever, a second lever for shifting said upper forming member relative to the lower forming member, and a disengageable connection between said presser-bar and said second lever for enabling the presser-foot, 120 the upper tuck-forming member and the tension release plate being controlled by a single lever when desired.

13. In a sewing machine, in combination, 125 stitch-forming mechanism including a plurality of needles, a presser-foot, a tucking device having upper and lower forming members located in advance of the needles, an arm supporting said upper forming member and extending from a point in front of 130

the needles to a position in rear of the needles, a bracket fixedly secured in rear of the needles, a sliding connection between said bracket and said arm, a vertically extending pin carried by said bracket, a tension release plate slidably supported on said vertically extending pin and a multiple tension device fixedly carried by said bracket in coöperative relation with said tension release plate, and common means for lifting 10 said upper forming member, said presser-foot and said tension release plate.

5 In testimony whereof, I have signed my name to this specification.

ALBERT H. DE VOE.
